WINDOW SCREEN

Stephen T. Kish, Passaic, N. J.

Application February 19, 1935, Serial No. 7,242

5 Claims. (Cl. 156—39)

This invention relate

This invention relate

This invention relates to certain new and useful improvements in window screens.

The primary object of the invention is to provide a window screen of the rolling type and of a character that may be permanently built into a window frame for association with the sliding sashes or in the form of an attachment adapted for placement in a window frame.

10 A further object of the invention is to provide a rolling window screen of the above character having a pair of tensioned rollers respectively carried by the head and base of the window frame with the free unwinding ends of the screen sections on the rollers adapted to be connected together 15 with the two screens extending over the entire window opening and with the meeting end of one screen section detachably engaged with the upper rail of the lower sliding sash whereby the lower screen section may be disconnected 20 from the upper screen section and wound on its roller with the upper sash slid downwardly and the opening caused thereby covered by the upper screen section.

With the above and other objects in view that will become apparent as the nature of the invention is better understood, the same consists in the novel form, combination and arrangement of parts hereinafter more fully described, shown in the accompanying drawings and claimed.

30 In the drawings:—

Figure 1 is a front elevational view of a window frame equipped with the rolling screens of the present invention, with the two screen sections detachably connected together at their unwinding free ends:

Figure 2 is a front elevational view with the lower rolling screen section wound on its roller and with the unwinding free ends of the upper screen section detachably engaged with the upper rail of the lower sash;

Figure 3 is a front elevational view with both screen sections wound on their rollers with the lower sash partly raised;

45 Figure 4 is a fragmentary front elevational view showing the hook and pin connection between the unwinding free ends of the two screen sections;

Figure 5 is a detail sectional view taken on line 5-5 of Figure 4;

50 Figure 6 is a vertical cross-sectional view taken on line 6—6 of Figure 1, showing the boxes or housings for the screen rollers, the unwinding free ends of the screen sections detachably connected together with the lower end of the upper

screen section detachably engaged with the upper rail of the lower sliding sash;

Figure 7 is a vertical longitudinal sectional view of the rolling screen and supporting structure therefor removed from the window frame;

Figure 8 is a fragmentary front elevational view of the window frame with the cover for the upper screen roller housing removed to illustrate the mounting of the screen roller;

Figure 9 is a detail sectional view of the upper end of the window frame, showing the key slot in the upper housing to receive the spring winding key of the screen roller; and

Figure 10 is a detail sectional view of the lower end of the window frame showing the housing to receive the lower screen roller and the slot therein for the spring winding key of the roller. 15

Referring more in detail to the accompanying drawings, there is illustrated a window frame comprising side bars 15, head and sill bars 16 20 and 17 respectively with vertically slideable upper and lower sashes 18 and 19 therein as shown more clearly in Figure 6.

The window screen may be built into the window frame as a permanent part thereof, or in the form of an attachment and as illustrated in Figure 7, the window screen and its carrying apparatus comprises head and sill housings 20 and 21 extending transversely of the window frame between the side bars 15 respectively adjacent the head bar 16 and the sill bar 17. The ends of the head and sill housings 20 and 21 adjacent the side bars 15 of the window frame are connected by a pair of vertical guides 22 between which guides the opposite side edges of rolling window screens travel.

Each of the housings 20 and 21 houses a tensioned roller 23, a rolling window screen 24 being wound on the roller 23 in the head housing 20, while a rolling window screen 25 is wound on the roller 23 in the sill housing 21. The unwinding free ends of the upper and lower screen sections 24 and 25 are respectively attached to the cross bars 26 and 27 and as shown in Figures 1 and 4 to 7, a pivoted hook 28 is carried by the bar 26 of the upper screen section 24 to be engaged with a pin 29 carried by the cross bar 27 of the lower screen section 25, the two screen sections 24 and 25 spanning the window opening. A pair of hinged hooks 30 depend from the outer lower corner edge of the cross bar 26 at the lower end of the upper screen section 24 to be engaged with the upper rail 31 of the lower sliding window sash 19, the outer side of the cross bar 27 of the lower screen section 25 being provided with cut- 55

away portions 32 providing clearances for the hooks 30.

As shown in Figures 7, 8 and 9, the head housing 20 carries a removable front wall 33 permitting access to the upper screen roller 23 and said wall carries shade roller brackets 34 and curtain pole brackets 35 at each end thereof. The end walls of the head housing 20 are provided with slotted openings 36 to provide the key end 37 of the upper screen roller 23 and said slotted opening 36 is closed by a key or wedge 38.

The sill housing 21 is provided with a removable cover 39 permitting access to the lower screen roller 23 and said removable cover 39 has a flanged inner side edge with a projecting lug 40 to be received in the opening 41 in the front wall of the sill housing 21 to aid in retaining the cover 39 in position. The end walls of the sill housing 21 are provided with slotted openings 36a similar to the slotted openings 36 in the head housing 20 to receive the key ends 37a of the lower screen roller 23 with the key ends retained in position by the key or wedge piece 38a inserted in the outer end of the slot 36a.

When the cross bars 26 and 27 of the two screen sections 24 and 25 are disconnected from each other and the hooks 30 carried by the upper screen section 34 are disengaged from the upper rail 31 of the lower sash 19, the tensioned rollers 33 in the sill housings 20 and 21 wind the screen sections 24 and 25 thereon and the cross bars 26 and 27 occupy the positions illustrated in Figure 3. When so disposed, the window opening is devoid of the screening device. As shown in Figure 1, the cross bars 26 and 27 of the two screen sections are engaged with each other by means of the hook and pin connections 28 and 29 with the screen sections 24 and 25 completely expanding the window opening. When so disposed, the hooks 30 carried by the upper screen section 24 engage with the upper rail 31 of the lower sliding sash 19 as shown in Figure 6 so that if desired, the lower screen section may be wound into the sill housing 21 and the upper screen section 24 remain in operative position should it be desired to lower the upper sliding sash 18, as shown in Figure 2.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

55 I claim:—

1. In a rolling window screen, head and sill casings respectively adjacent the head and sill bars of a window frame, vertical guides at each

side of the window frame connecting the casings, a roller screen in each casing having its side edges extending into adjacent guides, means for connecting the adjacent free ends of the two screens together and means for connecting the lower end of the upper screen to the upper rail of the lower sash.

2. In a rolling window screen, head and sill casings respectively adjacent the head and sill bars of a window frame, vertical guides at each side of the window frame connecting the casings, a roller screen in each casing having its side edges extending into adjacent guides, a cross bar carried by each adjacent end of the two screens, hook and pin connections between the two cross bars, and means for connecting the lower end of the upper screen section to the upper rail of the lower sash.

3. In a rolling window screen, head and sill casings respectively adjacent the head and sill bars of a window frame, vertical guides at each side of the window frame connecting the casings, a roller screen in each casing having its side edges extending into adjacent guides, a cross bar carried by each adjacent end of the two screens, hook and pin connections between the two cross bars, hooks depending from the cross bar on the upper screen for engagement with the upper rail of the lower sash and the cross bar of the lower screen having cut-away portions providing clearance for the hooks.

4. In a rolling window screen, head and sill casings respectively adjacent the head and sill bars of a window frame, vertical guides at each side of the window frame connecting the casings, a roller screen in each casing having its side edges extending into adjacent guides, a cross bar carried by each adjacent end of the two screens, hook and pin connections between the two cross bars, and means for connecting the lower end of the upper screen to the upper rail of the lower sash, said casings and guides with the two screens being unitarily removable from the window frame.

5. In a rolling window screen, head and sill casings respectively adjacent the head and sill bars of a window frame, vertical guides at each side of the window frame connecting the casings, a roller screen in each casing having its side edges extending into adjacent guides, a cross bar carried by each adjacent end of the two screens, hook and pin connections between the two cross bars, hooks depending from the cross bar on the upper screen for engagement with the upper rail of the lower sash and the cross bar of the lower screen having cut-away portions providing clearance for the hooks, said casings and guides with the two screens being unitarily removable from the window frame.

STEPHEN T. KISH.
